UNITED STATES PATENT OFFICE.

HENRY S. PRENTISS, OF ELIZABETH, NEW JERSEY.

TIME-SWITCH.

SPECIFICATION forming part of Letters Patent No. 632,145, dated August 29, 1899.

Application filed February 13, 1897. Serial No. 623,226. (No model.)

To all whom it may concern:

Be it known that I, HENRY S. PRENTISS, a citizen of the United States of America, and a resident of Elizabeth, in the county of Union 5 and State of New Jersey, have invented certain new and useful Improvements in Time-Switches, of which the following is a specification.

My invention has reference to improvements in time-switches for incandescent and 10 are circuits, and has for its objects, first, to provide means independent of the switch proper for acting directly on the switch-lever for the purpose of completely moving the lever 15 through its range; secondly, to prevent shunting of the current through the time-switch mechanism or any part thereof, and, thirdly, to insure positive action.

To this end my invention consists, essentially, in a time-switch embodying a usual 20 switch-lever, a spring-pressed lever adapted to engage with said switch-lever, a latch for retaining said spring-pressed lever, and an electromagnet having its armature placed in 25 connection with said latch for tripping the same to release the switch-operating lever when the electromagnet is energized for causing the latter to operate the switch-lever.

The nature of my invention will best be 30 understood when described in connection with the accompanying drawings, in which—

Figure 1 represents an elevation of a switch-board provided with my improved time-switch. Fig. 2 is a vertical section on the 35 line 2 2, Fig. 1. Fig. 3 is an elevation with part broken away, showing the switch-lever in its upper position. Fig. 4 is an elevation, on a smaller scale, of the entire apparatus. Fig. 5 is an elevation illustrating a modified 40 form. Fig. 6 is a vertical section thereof. Fig. 7 is an elevation showing the switch-lever in its upper position.

Similar letters and numerals of reference 45 designate corresponding parts throughout the several views of the drawings.

Referring at present to Figs. 1 to 4 of the drawings, the letter B designates the base of the switchboard, made of slate or other suitable material, to which is secured a usual circuit-closer or switch S of any construction, 50 containing a lever for making and breaking

the circuit. In the present instance I have illustrated a knife-switch embodying a lever L. The switch-operating mechanism consists of a lever 1, adapted to engage with the handle 2 or other portion of the switch-lever L to turn the same from its upper or circuit-closing position, as shown in Fig. 3, to its lower or circuit-breaking position, as shown in Fig. 1. Said lever is attached to a horizontal stud 3, mounted to turn in lugs formed on a suitable bracket C, secured to the base of the switchboard. Said stud is subjected to the action of a spiral spring 4, attached at one end to said stud, and at its other end 60 to the bracket C, or preferably to an adjusting-ring 5, so that its tension can be regulated. In the bracket C is mounted to slide vertically a latch D, formed with a lip 6, adapted to engage with and hold the horizontal portion 7 of the lever 1 when the latter is turned upwardly to the position shown in Fig. 3. The motion of said latch is limited by two stops 8 8. On the bracket C is mounted an electromagnet E, having a gravitating 75 armature 9 hinged to the bracket. The downward movement of the armature is limited by an adjustable stop 10, preferably made in the form of a screw, the head of which engages with said armature. The armature 9 is provided with an extension or arm 11, adapted to engage with the lower end of the latch D. 80

To set the switch-operating lever 1, it is turned upwardly to the position shown in Fig. 3 and by dotted lines in Fig. 2 and pressed 85 against the lip 6 of the latch D, the pressure springing the latch upwardly to permit the passage of the lever, whereupon the latch falls by gravity to retain the lever in its upper position. The switch-lever is then turned 90 upwardly to close the circuit, its handle 2 being then in front of and preferably a short distance from the arm 7 of lever 1. When the circuit is closed through the electromagnet E, the latch is thrown upwardly by the 95 blow of the extension or arm 11 and releases the lever 1, which in view of the force exerted by the spring 4 turns the switch-lever L downwardly to break the circuit, as shown in Figs. 1 and 2. To arrest the motion of the lever 1, a suitable stop or buffer 12 is provided. The lever 1 is also preferably pro-

vided with a suitable handle 13 of insulating material.

To operate the switch at a predetermined time, any suitable circuit-closer F—such, for 5 instance, as that shown in Fig. 4 and operated by a suitable motor or clock-movement—may be used, the wires 15 and 16, leading from a battery B*, being placed in connection with said circuit-closer and with the electromagnet 10 E. A suitable circuit-closer, such as the push-button c, is interpolated in the wires 15 and 16 to enable the switch to be operated by hand.

It will be readily understood that the time- 15 switch can be placed on the switchboard in a position to have all metallic parts at a greater distance from the posts of the switchboard than the distance between said posts, and consequently there is absolutely no danger 20 of the circuit being shunted.

In the construction shown in Figs. 5, 6, and 7 I have shown an armature-lever 14 placed above the cores of the electromagnet and arranged to swing about a pivot 17, it 25 being slightly overbalanced by a weight 18. It is also provided with an iron block 20, arranged to one side of one of the cores and in close proximity to the same. The outer end of the armature-lever is adapted to engage 30 with a pin 21 on the latch D for the purpose of tripping the switch-throwing lever when the armature-lever is attracted by the electromagnet. The purpose of this construction and arrangement for the armature-lever is to 35 reduce the battery-power required for operating the switch. In the present example I have also shown an extra insulating-ring 22, secured to the horizontal arm 7 of the lever 1, which engages with the handle of the switch- 40 lever L, and I have also shown the handle 13 made of rubber.

I do not wish to restrict myself to the details of construction of the device for actuating the switch-lever, as it is evident that 45 the same could be modified without departing from the spirit of my invention. Neither do I wish to restrict myself to the use of the specific device for actuating electric switches, as it is evident that it can be used for operating cocks, valves, and burners and for kindred purposes.

What I claim as new is—

1. A time - switch embodying the usual switch-lever coöperating with contacts for 55 making and breaking the circuit, a spring-pressed lever adapted to engage with said lever for turning the same about its pivot to break the circuit, a latch adapted to engage with and to retain the said lever in its operative 60 position, an electromagnet having its armature placed in connection with said latch for tripping the same to release the switch-operating lever when the electromagnet is energized for the purpose of turning the switch-lever to break the circuit, and a circuit-closer in the circuit of the electro- 65

magnet, all substantially as and for the purpose specified.

2. A time - switch embodying the usual switch-lever coöperating with contacts for 70 making and breaking the circuit, a spring-pressed lever adapted to engage with said lever for turning the same about its pivot to break the circuit, a latch mounted to slide and adapted to engage with and to retain the 75 said lever in its operative position, an electromagnet having its armature placed in connection with said latch for sliding the same to effect its disengagement from the switch-operating lever when the electromagnet is energized for the purpose of causing the switch-lever to be turned by the switch-operating lever to break the circuit, and a circuit-closer in the circuit of the electromagnet, substantially as described. 80

3. A time - switch embodying the usual switch-lever coöperating with contacts for 85 making and breaking the circuit, a spring-pressed lever adapted to engage with said lever for turning the same about its pivot to break the circuit and mounted to turn about a horizontal axis, a latch vertically disposed and adapted to engage with said spring-pressed lever to retain the same in its operative position, an electromagnet having its 90 armature placed in connection with said latch for sliding the same to effect its disengagement from the switch-operating lever when the electromagnet is energized for the purpose of causing the switch-lever to be 95 turned by the switch-operating lever to break the circuit, and a circuit-closer in the circuit of the electromagnet, substantially as described. 100

4. A time - switch embodying the usual 105 switch-lever coöperating with contacts for making and breaking the circuit, a spring-pressed lever adapted to engage with said lever for turning the same about its pivot to break the circuit, a latch adapted to engage 110 with and to retain the said lever in its operative position, an electromagnet having its armature placed in connection with said latch for tripping the same to release the switch-operating lever when the electromagnet 115 is energized for the purpose of turning the switch-lever to break the circuit, a circuit-closer in the circuit of the electromagnet, means for actuating the circuit-closer to close 120 the circuit at a predetermined time, and an independent source of electricity for the circuit of the circuit-closer, substantially as described.

In testimony that I claim the foregoing as my invention I have signed my name, in presence of two witnesses, this 3d day of February, 1897.

HENRY S. PRENTISS.
